DESIGN FOR AN AIRCRAFT PROPELLER

Ernest G. McCauley and Sidney M. Gamsu, Dayton, Ohio, assignors to McCauley Corporation, Dayton, Ohio, a corporation of Ohio

Application January 10, 1947, Serial No. 136,054

Term of patent 14 years

(Cl. D71—1)

To all whom it may concern:

Be it known that we, Ernest G. McCauley and Sidney M. Gamsu, citizens of the United States of America, residing at Dayton, in the county of Montgomery and State of Ohio, respectively, have invented a new, original, and ornamental Design for an Aircraft Propeller, of which the following is a specification, reference being had to the accompanying drawing, forming a part thereof.

Fig. 1 is a view in perspective from the forward side of an aircraft propeller showing our new design;

Fig. 2 is an enlarged view in perspective of the hub portion of the propeller shown in Fig. 1;

Fig. 3 is a view in elevation of the rearward side of the portion of the propeller shown in Fig. 2; and

Fig. 4 is a sectional view through the propeller taken substantially on the line 4—4 of Fig. 3.

The characteristic features of our design reside in the portions shown by means of full lines in the drawing.

We claim:

The ornamental design for an aircraft propeller, substantially as shown and described.

ERNEST G. McCAULEY.
SIDNEY M. GAMSU.
